PAPER-CONVEYING MECHANISM.

1,362,971.

Specification of Letters Patent.

Patented Dec. 21, 1920.

Application filed March 29, 1915. Serial No. 17,792.

To all whom it may concern:

Be it known that I, WALTER G. TRAUTMAN, a subject of the Emperor of Germany, residing at Cleveland, in the county of Cuyahoga and State of Ohio, have invented certain new and useful Improvements in Paper-Conveying Mechanism, of which the following is a specification.

My invention relates to improvements in paper conveying mechanism for paper folding machines and the like, and has for its object, the provision of means for advancing the folded sheets or signatures to paired conveying rolls or other mechanism, with certainty and expedition.

In the patent to Johnson, No. 893,629, July 21st, 1908, there is shown a paper folding machine equipped with paired co-acting rolls adapted to advance the folded sheets laterally when the same are drawn between the rolls. In practice it is found quite frequently that the signatures will be impeded in their course from the folding rolls to the conveying rolls, either through charges of static electricity or friction, which may be augmented with signatures formed of relatively heavy stock tending to spring apart at the fold. Signatures formed of light stock, on the other hand, do not have sufficient weight or momentum, and often stick in the machine. Accordingly, it has been my purpose to provide paper conveying mechanism with means for overcoming these tendencies; which means obviously must not appreciably impede the lateral or other travel of the paper. My improvements which are shown in a paper folding machine, respond to the requirements named.

The present improvements comprise one or more paired sets of driven rotatable members, between which the paper is adapted to be rapidly passed, and preferably these rotatable members comprise small flexible rotary brushes which peripherally engage or intersect when the paper is not passing therebetween. One roll may thus be used to drive the other, if desired.

Further details of my improvements will now be explained in connection with the accompanying drawings, wherein:

Figure 1 is a fragmentary view in end elevation of a folding machine centrally broken away, and equipped with my improvements.

Fig. 2 is an enlarged fragmentary view of

the transverse paper conveying mechanism, with which are associated the rotary auxiliary members or brushes above referred to, and

Fig. 3, is another enlarged view showing in plan, this same mechanism.

Throughout the several figures of the drawings, I have employed the same character of reference to indicate similar parts.

Referring first to Fig. 1, which shows only enough of the folding machine construction, centrally broken away, to identify the function and use of my improvement, it will be understood that said machine is provided with sets of geared folding rolls as positioned in the upper portion of the frame *b* and driven by left hand gears under power transmitted from the pulley wheel *c*. The normal course of the paper or signature from the last set of folding rolls is vertically downward between the paired guide rods *d*, until the signature is seized between the co-acting spring-pressed rolls *ee*, which seat it within the grooved guide *e'* and pass said signature to the right and into the buckling plate *f*, which is shown extending upon that side of the figure.

As stated, the progress of the paper not uncommonly is seriously impeded from different contributing causes, so that the folding machine may not be driven at full capacity, but the simple auxiliary mechanism associated with these rolls *ee* effectively overcomes the tendency in question. This mechanism I will now describe by referring to the large figures of the drawings which are better adapted to this purpose.

Referring next to Fig. 2, it is seen that the vertical bars *d* form frames positioned upon opposite sides of a slight groove, formed in the transverse guide *e'*. Two sets of spring-pressed rolls *e* set at a slight angle with the vertical bars, are positioned to engage immediately above the groove. In Fig. 2, the direction of the lateral movement of the paper would be toward the left, and these rolls serve to seize and advance the paper rapidly as soon as it comes between their engaging surfaces. Each roll is provided with a frusto-conical upper portion *e''* and a finely knurled cylindrical portion *e'*. The farther one of said rolls is equipped with a short upright shaft *e'*, whereon there is mounted one of the paired beveled gears *g' g''*. The latter gear *g''* is mounted upon a rotatable

2
sleeve g approximately at right angles to said shaft, which bears one of the engaging rotatable brushes h h' . The latter brush may be adjusted toward and from the geared 5 brush, by means of a thumb screw i , which acts against the spring i' to cause the brush h' lightly to engage its co-acting brush h .

When the folding machine is in operation, the transverse conveying rolls will be rapidly 10 driven by means of the co-acting gears g^a and the beveled gears g' g'' in turn, will impart motion to the brush h , which rapidly rotates the co-acting brush h' . These brushes serve lightly to impel the paper, 15 folded sheet or signature, directly between the transverse conveying rolls and seat it upon the grooved support, accurately to advance the paper into the angularly positioned buckling plate f .

20 However, the lateral travel of the signature within the grooved guide e' toward the buckling plate, is practically unimpeded by the engaging brushes, one of which ceases to rotate as soon as the paper intervenes between 25 the peripheries of these flexible rotary members. (See Fig. 3).

It will be understood that the number of paired rotary brushes may be increased, if desired, and these may be disposed in other 30 positions than immediately adjacent to the transverse conveying rolls as specifically shown and described. It is important to observe, nevertheless, that these rotary brushes or their equivalents, are flexible and 35 capable of relative adjustment so that while they serve to drag the signatures rapidly between the transverse conveying rolls and thereby assist the momentum thereof and gravity as well, said brushes do not impede the travel of the signature at right angles, as would rolls of more rigid material, 40 tapes, or other similar members previously employed as conveyers in folding machines and the like.

45 In Fig. 3 I have illustrated the operation of the co-acting rotary brushes, which preferably are maintained in a position of engagement with the tips of the brush members slightly interlacing except during the 50 passage of a sheet or signature therebetween. One of said members, as explained, then becomes an idler, and the bristles forming said brushes are bent slightly in the direction of the lateral travel of the paper, 55 immediately it is grasped between the rolls, ee , for advancing the same into the buckling plate.

My invention is not restricted to the precise details herein set forth, nor to the particular brush members just explained, since 60 these specific rotary members may be advantageously employed in other relations and other positions in paper conveying machinery, without departing from the spirit 65 of my invention.

Accordingly, I claim as new, and desire to secure by Letters Patent, the following:

1. In a paper conveying mechanism, the combination with transverse conveying members adapted to seize and impel folded sheets and the like, of flexible rotary members positioned adjacent thereto in the line of travel of said folded sheets, and means for rapidly rotating the same, substantially as set forth. 75

2. In paper conveying mechanism, the combination with a grooved guide adapted to receive the edge of the folded sheet, of paired co-acting rolls positioned to impel the sheet along said guide, narrow circular brush 80 members positioned in advance of said co-acting rolls, and adapted to direct the folded sheet therebetween, and means for driving said rolls and members, substantially as set forth. 85

3. In paper conveying mechanism, the combination with a horizontal guide, of paired rolls engaging above said guide, a vertical frame positioned above the rolls and guide between which sheets of paper are adapted 90 to be passed, paired co-acting brushes positioned in advance of said rolls and adapted to direct the sheets of paper through the frame and between said rolls, and means for rapidly rotating the rolls and brushes, 95 substantially as set forth.

4. In paper conveying mechanism the combination with a frame through which sheets of paper are adapted to be passed, of means adjacent to both ends of said frame 100 for advancing the paper, intermediate paired co-acting rotary brushes positioned to engage and direct the paper through said frame, and means for rapidly rotating the brushes, substantially as set forth. 105

5. In paper conveying mechanism, the combination with a frame or support along which sheets of paper are adapted to be passed, of means for conveying the paper to and from the same, paired engaging rotary brush members positioned intermediate of the frame to engage the paper and impel it along said frame or support, and means for rotating one of said brush members, substantially as set forth. 110

6. In a paper conveying mechanism, the combination with a frame or support along which sheets of paper are adapted to be passed, of paired driven rotary brush members positioned to engage the paper and impel it along said frame or support, and means for withdrawing the paper by a secondary movement thereof, from between said brush members, substantially as set forth. 115

7. In a paper conveying mechanism, the combination with a vertical frame through which sheets of paper are adapted to be passed by gravity, of paired driven brush members positioned to engage the paper, and 120

125

130

impel it along said frame, and means for impelling the paper from between said brush members at an angle with its initial path of movement, substantially as set forth.

8. A transverse paper-feeding or conveying mechanism, comprising a guide, paired rolls positioned adjacent to said guide and adapted to direct the paper along the same, and 10 paired rotatable brushes disposed at substantially right angles with said rolls and closely adjacent thereto, for concurrently acting upon the signature to enter it between the rolls and seat it upon the guide, substantially as set forth.

9. A transverse paper-feeding or conveying mechanism, comprising a frame in vertical position, a guide beneath said frame, paired rolls upon opposite sides of said guide 20 adapted to direct the signature along the same, paired rotatable brushes positioned substantially at right angles with and imme-

diate before said rolls for concurrently acting upon the signature to maintain its position against the guide, and means for 25 rotating said rolls and brushes, substantially as set forth.

10. A paper conveying mechanism, comprising a frame along which the signatures are passed, circular flexible paired brushes 30 adapted to impel said signature, a grooved guide or support beyond the brushes, paired rolls substantially at right angles with the brushes and positioned to direct the paper along the support substantially at right angles with its initial course between the 35 brushes, and means for driving said rolls and brushes, substantially as set forth.

In testimony whereof I do now affix my signature in the presence of two witnesses. 40
